[57] **CLAIM**

The ornamental design for a combined expansion chamber metered dose inhaler dispenser and adaptor, as shown and described.

DESCRIPTION

FIG. 1 is a perspective view showing the rear, top, and right end of the invention;

FIG. 2 is a top view thereof;

FIG. 3 is a front elevational view thereof;

FIG. 4 is a right end view of the invention oriented as shown in FIG. 1; and,

FIG. 5 is a left end elevational view of the invention as oriented in FIG. 1.

FIG. 1

FIG. 4

FIG. 2

FIG. 3

FIG. 5
